Primary Examiner — Eliza Z Harvey(57) **CLAIM**

The ornamental design for a universal wall mount, as shown and described.

DESCRIPTION

FIG. 1 is a top right front perspective view of a design for a universal wall mount in a first position;

FIG. 2 is a front view of the design for the universal wall mount in the first position;

FIG. 3 is a rear view of the design for the universal wall mount in the first position;

FIG. 4 is a left side view of the design for the universal wall mount in the first position;

FIG. 5 is a right side view of the design for the universal wall mount in the first position;

FIG. 6 is a top view of the design for the universal wall mount in the first position; and,

FIG. 7 is a bottom view of the design for the universal wall mount in the first position.

The features shown in broken lines depict environmental structure only and form no part of the claimed design.
